UNITED STATES PATENT OFFICE.

GIOVANNI EMANUELE ELIA, OF WESTMINSTER, LONDON, ENGLAND, ASSIGNOR TO
VICKERS LIMITED, OF LONDON, ENGLAND.

SUBMARINE MINE.

Application filed September 13, 1920. Serial No. 409,761.

To all whom it may concern:

Be it known that I, GIOVANNI EMANUELE ELIA, a subject of the King of Italy, residing at Vickers House, Broadway, West-
5 minster, in the county of London, England, have invented certain new and useful Im-
provements in or Relating to Submarine Mines, of which the following is a specifica-
tion.

10 This invention relates to submarine mines of the kind comprising an anchor connected to the flotation chamber or mine proper by a mooring cable. The invention has more especial reference to mines in which the pay-
ing out of the mooring cable is effected by the separation of the flotation chamber from the anchor after the mine has been launched and the parts thereof approach or reach the sea bed and in which a weight is provided
15 20 for arresting the unwinding or paying out of the mooring cable, the said weight being normally held attached to the mooring cable and being released therefrom at a predetermined point in the ascent of the flotation
25 chamber so as to regulate the depth of im-
mersion at which the flotation chamber will be anchored.

In mines of this type a plummet or sound-
ing ball has usually been provided, which
30 controls the separation of the flotation chamber from the anchor by preventing paying out of the mooring cable from the winch drum which carries the same until the mine approaches or reaches the sea bed and one
35 feature of the present invention consists in dispensing with the aforesaid plummet or sounding ball and in providing retaining means (hereinafter termed anchor arms) carried by the anchor which normally form
40 a cage or cradle for connecting the flotation chamber to the anchor until the mine has been launched and has reached the sea bed, said retaining means also assisting in anchoring the mine after the flotation chamber
45 and the anchor have separated from each other to a predetermined extent.

To this end a number of anchor arms, for example four, may be pivotally connected to the base plate or lower casting of the anchor,
50 which arms normally project vertically up-
wards so as to surround the flotation cham-

ber when the latter is in position on the anchor. At or towards the upper end of each of the aforesaid arms a tie rod may be attached, the ends of the several tie rods 55 being brought together at the top of the mine and secured in a detachable manner to each other so as to retain the flotation chamber in contact with the anchor until it is desired that they shall separate. Such means 60 may comprise a soluble plug which is adapted after the mine has been launched and has reached the sea bed to dissolve and to release the retaining means for the tie rods so that owing to the buoyancy of the flotation chamber and its normal tendency to rise clear of the anchor the anchor arms are thrown radially outwards about their pivotal connections and the flotation chamber separates 65 from the anchor. When the anchor arms 70 have fulfilled their function as retaining means they rest upon the sea bed and serve as an additional anchoring means for the mine.

A further feature of the present invention 75 consists in providing suitable means, herein-
after term "tracks," which are carried by or form part of the anchor and the flotation chamber and which are of such a character as to permit the mine to be launched by 80 rolling the same upon the said tracks, thus dispensing with the necessity of providing wheels on the anchor and a special launching track on the ship or vessel which carries the mine.

Such special launching means may be formed by three circular metal tracks, which are of slightly larger diameter than the flotation chamber or the anchor. Two of these tracks may be constituted by circular cast- 85 90 95 ings which form respectively the top and bottom plates of the anchor. The third track may be constituted by a metal ring which encircles the flotation chamber at or about the centre of its periphery and which may be constructed in four separate or separable segments attached to the aforesaid anchor arms in such manner that when the anchor arms are released by the dissolution of the aforesaid soluble plug the upper seg- 100 mental track is also released and falls with the anchor arms to the sea bed.

In order that the said invention may be clearly understood and readily carried into effect the same will now be described more fully with reference to the accompanying drawings which show by way of example a submarine mine constructed according to the present invention and in which:—

Figure 1 is a part sectional elevation,

Figure 2 is an elevation with the aforesaid tie rods and the retaining means therefor in section so that the construction of these parts may be more clearly seen.

Figure 3 is a sectional plan view of the anchor.

Figure 4 is a sectional elevation,

Figure 5 is an outside elevation, and

Figure 6 is a sectional plan view of the aforesaid weight,

Figure 7 is a partly diagrammatic view showing the mine resting on its side upon the aforesaid tracks in which position it is ready to be launched.

Figure 8 is a view of the mine after it has been launched and is entering the sea,

Figure 9 shows the mine after it has reached the sea bed.

Figure 10 shows the approximate position assumed by the parts of the mine after the soluble plug has dissolved and the flotation chamber and the weight have commenced to separate from the anchor, and,

Figure 11 shows the relative position of the parts of the mine after the weight has been released and has operated to prevent continued paying out of the mooring cable, the flotation chamber being therefore anchored at the desired depth of immersion.

A is the flotation chamber, B is the anchor and C is the weight which is normally secured in a detachable manner to the mooring cable and which is released at the proper moment to determine the final depth of immersion of the flotation chamber. D is the mooring cable and E

is the mooring cable winch drum. F, F are the aforesaid tracks on which the mine is rolled from the ship or aeroplane during the act of launching. G, G are the anchor arms which in the example shown are four

in number and g, g are tie rods each of which is attached at g' to the anchor arms G, the other ends of the tie rods being brought together, as shown, at the top of the mine and secured to each other through

the intermediary of a coupling member g² which engages with an eye g⁶ on each of the tie rods g. The coupling member g² is held in engagement with the upper ends of the tie rods g by means of a soluble plug

g³ disposed around an attaching bolt g⁴ and by a nut g⁵ carried by a plate g⁷ and engaging the end of the bolt g⁴ above the soluble plug g³. Owing to this arrangement the soluble plug g³ and nut g⁵ normally

serve to hold the parts together but when the plug g³ is dissolved by the action of the sea water, the buoyancy of the flotation chamber A forces the member g² out of engagement with the eyes g⁶ in the tie rods g. H is a brake of the dash-pot type for controlling the speed at which the mooring cable is allowed to pay out from the winch drum E, the said brake being provided with a micrometer attachment so that the speed at which the flotation chamber A, and the weight C rises towards the surface of the water may be predetermined. The lower end of the winch drum E is formed with a ratchet toothed periphery e, and pivotally mounted on one of the uprights b which serve to connect together the upper and lower plates or tracks F, F, is a pawl e'. At its front end the said pawl e' is suitably shaped to engage when desired with the ratchet teeth e and stop the rotation of the winch drum, and at its other end it is acted upon by a spring e² which normally tends to oscillate it about its pivot and force it into engagement with the said ratchet teeth e. The pawl e' is normally held out of engagement with the ratchet teeth e by means of a vertical rod i, the lower end of which engages within a recess e³ in the pawl, the rod i being attached at its upper end to a member I which is adapted to be acted upon by the weight C when the latter is released at the desired moment from the mooring cable D. The said member I is formed in two parts, i' and i² respectively, which are pivotally connected together by a link member i³, the part i² being also pivotally connected at i⁴ to the upper part of the anchor casing. The rod i is slidably mounted in guides b', b' carried by one of the uprights b and a helical spring i⁵ is provided which acts on a stop i⁶ attached to the rod i in such manner as normally to retain the lower end of the said rod within the opening e³ in the pawl e'. The upper end of the part i' of the member I is provided with a fairlead i⁷ through which the mooring cable D is passed.

The winch drum E is provided at its upper part with teeth J, with which a bevel wheel j attached to a shaft j² having a handle j', is adapted to engage, these parts being operated when winding or unwinding by hand the cable D on or off the drum E.

The shaft j² is also provided with an extension j³ which engages the hollow spindle L around which the mooring cable drum is adapted to rotate. The mooring cable D which is to be attached to the flotation chamber is let off the winch drum E and passes around a pulley wheel d which is rotatably mounted upon the base plate F of the anchor. After passing round the pulley d the mooring cable is passed through the

hollow spindle L and the fairlead i⁷, and attached to the flotation chamber at a.

The weight C is of the type described and illustrated in United States Patents 5 Nos. 1,303,272 and 1,296,376; when the mine is out of the water and before it reaches the sea bed the hydrostat is maintained inoperative by means of a device of the type referred to in the aforesaid prior patents 10 which is withdrawn so as to release the hydrostat when the parts of the mine separate after having reached the sea bed.

The weight C is normally attached to a sleeve c which is fixed to the mooring cable 15 D a short distance away from the flotation chamber A and it is retained in position on the sleeve c by means of a pivotally mounted cranked lever c' which is located in a recess in the weight C and the long 20 arm of which engages within a recess c² in the sleeve c, the said recess c² being bevelled at its extremities as shown. The long arm of the lever c' is normally held in engagement with the aforesaid recess c by means 25 of a compression spring c³, while the short arm c⁴ of the lever c³ normally engages a notch c⁵ in a second cranked lever c⁶ which is pivotally mounted at c⁷ to the weight C and is attached at c⁸ by means of an elongated slot to a pair of lugs c⁹ on the movable part c¹⁰ of a hydrostatic device c¹¹. The short arm c¹² of the lever c⁶ is acted upon by means of a movable piston or 30 plunger c¹³ which surrounds the sleeve c and which is pressed downwards by means 35 of a compression spring c¹⁴, the extent of the pressure being capable of being varied as desired so as to determine the pressure and consequently the depth at which the 40 weight is to be released from the mooring cable. To this end an externally screw threaded plug c¹⁵ is provided which when rotated by a milled nut c¹⁶ compresses or relaxes the spring c¹⁴ by causing the plug c¹⁵ to advance or recede within a screw 45 threaded opening c¹⁷ in the weight C. Owing to this arrangement and when the flotation chamber A, carrying with it the upper end of the mooring cable D and also 50 the weight C, ascends from the sea bed towards the surface of the water the pressure of the sea water on the hydrostatic device and on the face of the piston or plunger c¹³ is gradually relaxed until it is reduced 55 to such an extent that it is less than the pressure exerted by the spring c¹⁴ on the end c¹² of the lever c⁶, this pressure corresponding to the depth at which the mine is to be anchored. Thereupon the lever c⁶ moves 60 about its fulcrum into a position in which the notch c⁵ disengages the extremity c⁴ of the lever c', so that the weight of the weight C is thrown entirely upon the long arm of the lever c', thereby overcoming the pressure 65 of the spring c³ and forcing the lever

c' out of engagement with the notch c² in the sleeve c. The weight is thus released and glides along the mooring cable towards the anchor.

In operation, the mine with the parts 70 locked together as shown in Figure 7 is launched by being located upon its side on the tracks F and rolled clear of the ship, aeroplane, or the like upon which it is supported. When the parts reach the sea bed 75 as shown at Figure 9, the soluble plug g³ dissolves and frees the tie rods g so that the anchor arms G fall downwards into the position shown in Figure 10 thus releasing 80 the flotation chamber which by its buoyancy commences to ascend towards the surface of the water. The mooring cable at the same time commences to pay out at a speed which is determined by the brake H. As the cable D pays out through the fairlead 85 i⁷ it raises the upper end i' of the member I into a vertical position as shown at Figure 10. When the mine ascends to the distance below the surface of the water for which the hydrostatic device has been set, 90 the weight C is released as aforesaid and in falling it strikes the upper end i' of the member I and thereby oscillates the part i² of the member I about its fulcrum i⁴, thus raising the rod i out of engagement with the 95 opening e³ in the pawl e' and allowing the pawl e' to be forced by the spring e² into engagement with the ratchet teeth e on the mooring cable winch drum E. The flotation chamber is thus anchored at a predetermined 100 distance below the surface of the water while the pawl e effectually locks the winch drum against continued rotation thereby preventing further paying out of 105 the mooring cable.

What I claim and desire to secure by Letters Patent of the United States is:—

1. A submarine mine comprising a flotation chamber, an anchor, rigid anchor arms pivotally attached to the base plate of the 110 anchor which normally extend vertically upwards and form a cradle for the flotation chamber, tie rods connected at one of their ends to the anchor arms, the ends of the tie rods being brought together at the top 115 of the flotation chamber, retaining means comprising a soluble plug for securing said tie rods together in a detachable manner until after launching of the mine, said anchor arms, when the tie rods are released, acting 120 as anchoring means for the mine.

2. A submarine mine comprising a flotation chamber, an anchor, rigid anchor arms attached to said anchor which normally extend vertically upwards, and form a cradle for the flotation chamber, and launching tracks forming part of the anchor and of 125 said anchor arms which permit the mine to be launched by rolling the same upon said tracks.

3. A submarine mine comprising a flotation chamber, an anchor, rigid anchor arms which normally extend upwards and form a cradle for the flotation chamber and launching tracks which permit the mine to be launched by rolling the same upon the said tracks said launching tracks being constituted by circular castings forming respectively the top and bottom plates of the anchor and by ring segments attached to the anchor arms and normally encircling the flotation chamber.

In testimony whereof I affix my signature.
GIOVANNI EMANUELE ELIA.
